(57) **CLAIM**

The ornamental design for a pet boundary transmitter, as
shown and described.

DESCRIPTION

FIG. 1 is a perspective view of a pet boundary transmitter,
under a first embodiment.

FIG. 2 is a top view thereof.

FIG. 3 is a bottom view thereof.

FIG. 4 is a front view thereof.

FIG. 5 is a rear view thereof.

FIG. 6 is a left view thereof.

FIG. 7 is a right view thereof.

FIG. 8 is a perspective view of a pet boundary transmitter,
under a second embodiment.

FIG. 9 is a top view thereof.

FIG. 10 is a bottom view thereof.

FIG. 11 is a front view thereof.

FIG. 12 is a rear view thereof.

FIG. 13 is a left view thereof; and,

FIG. 14 is a right view thereof.

The broken lines illustrate portions of the pet boundary
transmitter that form no part of the claimed design.

1 Claim, 10 Drawing Sheets
